UNITED STATES PATENT OFFICE.

WELLS R. STOKELY, OF ST. AUGUSTINE, FLORIDA.

CAR-REFRIGERATOR.

No. 927,820.

Specification of Letters Patent.

Patented July 13, 1909.

Application filed April 2, 1908. Serial No. 424,800.

To all whom it may concern:

Be it known that I, WELLS R. STOKELY, a citizen of the United States, residing at St. Augustine, in the county of St. Johns and 5 State of Florida, have invented new and useful Improvements in Car Refrigeration, of which the following is a specification.

My invention pertains to cars, and more particularly to cars constructed for the transportation of fruit; and it contemplates the provision in combination with means for leading atmospheric air into the interior of a car and exhausting vitiated air from such interior, of means whereby the temperature 15 of the air while passing from the atmosphere to the interior of the car may be tempered—*i. e.*, cooled or heated, in order to avoid injury to the fruit being carried in either warm or cold weather.

With the foregoing in mind, the nature of the invention and its novelty, utility and practical advantages will be fully understood from the following description and claim when the same are read in connection 25 with the drawings, accompanying and forming part of this specification, in which:

Figure 1 is a vertical transverse section showing a car body and my improvements; the upper portion of the body being broken 30 away. Fig. 2 is a detail horizontal section of a portion of the car body taken in a plane below the foraminous false floor of the body, and above the air conduits. Fig. 3 is an enlarged longitudinal, vertical section of one 35 of the tanks comprised in my improvements.

Referring by letter to the said drawings: A is a car body which is preferably provided with means for exhausting the same of vitiated or foul air. The said means, however, 40 forms no part of my present invention, and therefore I have deemed it unnecessary to illustrate the same. At about the distance illustrated above its floor *a* the body A is provided with a foraminous false floor *b*, as shown in Fig. 1.

C C are tanks suspended below the body A and arranged longitudinally adjacent to the sides of the body, and D D are pipes contained in and extending longitudinally of 50 the said tanks. The tanks C and their systems of pipes are similar in construction, and therefore a detailed description of the tank C shown in Fig. 2 and the system of pipes used in combination with said tank, 55 will suffice to impart a definite understanding of both tanks and pipe systems.

The pipes D extend longitudinally through the tank at points adjacent to the bottom of the latter, and each pipe is connected at its outer end to an inductor E arranged exteriorly of the body A and preferably adjacent to a side wall thereof. From its inductor E each pipe D extends inwardly through the side wall of the body A and into the space between the floor *a* and the false floor *b* and 60 then downward through the floor *a* and into the tank C adjacent to one end thereof, and then after being carried longitudinally through the lower portion of the tank to a point adjacent to the opposite end thereof is 65 carried upward through the tank and the floor *a* of the body into the space between said floor *a* and the false floor *b*. Some of the pipes are arranged to discharge at *c* in the space between the floors *a* and *b*, while 70 other pipes are arranged to discharge at *d* in the upper portions of the corners of the body, and hence it will be manifest that the fresh air taken into the interior of the car will be distributed throughout such interior, 75 and also that the air currents discharged at the points *c* will meet the air currents discharged at the points *d* and in that way give rise to an agitation of air conducive to the thorough dissemination of fresh air 80 through the fruit or other perishable freight carried in the body. Each inductor E is preferably pivoted at *e* to its respective pipe D and is adapted to be reversed—*i. e.*, swung from the position shown in Fig. 2 to the opposite position, this latter in order that when the car is to travel in the direction opposite to the arrow No. 1, the inductors may be arranged to the best advantage in order to assure the plentiful supply of fresh air 85 to the interior of the body A.

The tanks C may be provided with any suitable means for tempering, that is—cooling or heating the air while the same is *en route* through the pipes D, and from this it 90 follows that in warm weather the air may be cooled precedent to the supply of the same to the interior of the body A, and in cold weather the air may be heated before the same enters the interior of the body. 105 As shown, each tank C is provided with a removable foraminous bottom *g*, curved in conformity to and resting close against the series of pipes D, a plurality of removable transverse partitions *h*, and a hinged door *i*. 110 As will be readily understood ice may be readily placed in the tanks C when the doors

i thereof are open, and it will also be understood that such ice will cool the air while the same is *en route* through the pipes D, and that the transverse partitions h will effectually prevent the ice threshing about and moving from end to end of the tanks incidental to the movements of the car and the passage of the same up and down sharp grades and will also effectually prevent collection of the ice in one end of the tank. It will further be noted in this connection that the foraminous bottom g will protect the pipes D against ice roughly thrown into the tanks, and this without interfering with the proper cooling of the said pipes. The adaptability of the bottoms g and the transverse partitions h to be removed from the tanks is advantageous inasmuch as it permits of said bottom and partitions and the pipes D being repaired with facility when occasion demands.

With a view of draining the pipes D of any water that may be deposited in the same by the air passing therethrough, the said pipes may be equipped at convenient points with drain cocks, but these form no part of my invention and hence I have deemed it unnecessary to illustrate the same.

When necessary the tanks C may be supplied with a suitable heating agent instead of the cooling agent described.

The construction herein illustrated and described constitutes the best practical embodiment of my invention known to me since it assures the maintenance of dry and pure air in the interior of the car at all times, and this without detracting from the carrying capacity of the car or greatly increasing the cost of the same; and the maintenance of dry air in the interior of the car will be appreciated as an important advantage when it is considered that both the car and the con-

tents thereof are kept dry, and hence when the car is unloaded it may be immediately reloaded with any commodity that it is desired to transport without the necessity of waiting for the car to dry out.

I prefer in practice to detachably connect the transverse partitions h to lugs h' on the major portions of the tank C, and to depend on the interposition of the foraminous bottoms g between the pipes D and the partitions h to retain the said bottoms in position, but it is obvious that the partitions and the bottoms may be detachably secured in the tanks in any approved manner without involving departure from the scope of my invention as defined in the claim appended.

Having described my invention, what I claim and desire to secure by Letters-Patent, is:—

The combination of a car body, a tank carried by and extending in the direction of the length of the body; said tank being circular in cross-section and having a major portion and a door hinged thereto, conduits extending longitudinally through the tank and arranged side by side on the bottom thereof and connecting the interior of the body with the atmosphere, a bottom curved in the direction of the width and removably arranged on said conduits, and transverse partitions detachably fixed in the tank and arranged above and in engagement with the said bottom to hold the same down upon the conduits.

In testimony whereof I have hereunto set my hand in presence of two subscribing witnesses.

WELLS R. STOKELY.
